Application April 5, 1934, Serial No. 719,215
Renewed January 17, 1938

35 Claims. (Cl. 22—57.5)

This invention relates to a method of and apparatus for shaping plastic material and it has particular relation to a method of and apparatus for continuously solidifying and shaping material which is fluid when subjected to heat, such as is disclosed in my co-pending continuing application, Serial No. 636,080, filed October 3, 1932 of which this application is a continuation in part.

In order to make the invention more clearly understood there are shown in the accompanying drawings, means for carrying the invention into practical effect, without limiting the improvements in their useful application to the particular construction, which for the purpose of explanation has been made the subject of illustration.

In the accompanying drawings:

Fig. 1 is a plan view of an apparatus constructed in accordance with the present invention.

Fig. 2 is a side elevational view of the structure illustrated in Fig. 1.

Fig. 3 is a vertical longitudinal sectional view taken on line 3—3 of Fig. 1.

Fig. 4 is a vertical longitudinal sectional view taken on line 4—4 of Fig. 1.

Fig. 5 is an end view of the structure shown in Fig. 1.

Fig. 6 is a vertical transverse sectional view taken on line 6—6 of Fig. 1.

Fig. 7 is a vertical transverse sectional view taken on line 7—7 of Fig. 1.

Fig. 8 is a view similar to Fig. 7 but illustrating the cooling and shaping rolls separated to interrupt the supply of plastic material thereto and to also discharge material delivered to the chamber between the rolls.

Fig. 9 is a diagrammatic view illustrating two pairs of cooling and shaping rolls, the arrows indicating the direction of rotation thereof when it is desired to obtain a single sheet from the left hand rolls, as viewed in this figure.

Fig. 10 is a similar view illustrating the direction of rotation of the rolls when it is desired to obtain a single sheet from the right hand pair of rolls, as viewed in this figure.

Fig. 11 is a similar view illustrating the direction of rotation of the rolls when it is desired to obtain two sheets simultaneously from opposite sides of the apparatus.

Fig. 12 is a similar view illustrating the direction of the rolls when it is desired to deliver a single sheet downwardly between the lower rolls of the cooperating pairs of rolls, and

Fig. 13 is a diagrammatic view illustrating the direction of flow of the several temperature con-

trolling media through the different rolls and in the vicinity of the material being delivered thereto.

Fig. 14 is a diagrammatic view of the thermo-responsive means for automatically varying the speed of rotation of the rolls in accordance with the temperature of the metal.

Referring to the drawings, an apparatus embodying the present invention is shown as comprising a base 1 preferably of cast construction, 10 suitably anchored upon a concrete foundation 2, and having a pair of parallel frame members 3 secured thereto along its edges at what may be termed the front and rear of the apparatus, which frame members are tied together adjacent their ends by plates 4 reinforced by channel bars 5 secured to the under sides thereof. Mounted in bearings 6 provided on the frame members 3, is a pair of parallel longitudinally extending shafts 7 upon each of which a pair of carriages 8 or pedestals 8 are mounted, one at each end, for lateral swinging movement. The carriages 8 of each pair are maintained in spaced relation with respect to one another and in abutting relation to the frame members 3, by means of a back up roll 9 of solid construction and also by means of a pair of upper and lower cooling and shaping rolls 10 and 11 respectively.

The lower rolls 11 are supported directly by the back up rolls 9 and comprise tubular shafts 12 the ends of which are journaled in floating bearings 13 (Fig. 3) which are mounted for vertical sliding movement in ways 14 provided in the carriages 8. The intermediate portions of the shafts 12 are formed with spaced collars 15 upon which outer cylindrical shells 16 are fixed, preferably by shrinking. The collars 15 are formed with openings 17, the openings in adjacent collars being staggered or offset circumferentially relative to one another so as to cause a cooling medium to traverse a tortuous path in passing through the rolls from end to end, as will hereinafter be described. The tubular shafts 12 are provided with partitions 18 (Fig. 3) intermediate their ends and also with openings 19 adjacent to the ends of the rolls for establishing communication between the tubular shafts and the interior of the lower rolls at each end thereof.

A temperature controlling medium which may be cold water or steam according to the nature of the material shaped by the rolls, is directed through one of the lower rolls 11 from end to end in one direction and through the other of the lower rolls 11 in an opposite direction, from flexible inlet pipes 20, the upper ends of which

are secured by means of clamping straps 21 to tubular flanged nipples 22 which are bolted to the outer surfaces of the floating bearings 13 in axial alignment with the tubular shafts 12. The 5 lower ends of the inlet pipes 20 are secured by clamping straps 23 to flanged nipples 24 mounted on inlet valves 25 which control communication between the inlet pipes 20 and supply mains or conduits 26 located at the front and rear of the 10 apparatus.

10 After passing through the lower rolls 11 the temperature controlling medium escapes from these rolls through flexible outlet pipes 27 the upper ends of which are secured by means of clamping straps 28 (Figs. 2 and 3) to flanged nipples 29 which are bolted to the floating bearings 13 at the other end of the rolls. The lower ends of the outlet pipes 27 are secured by clamping straps 30 to flanged nipples 31 which communicate with discharge mains 32 also located at 15 the front and rear of the apparatus.

15 The upper rolls 10 of each of the pairs of rolls are of slightly less diameter than the lower rolls 11 but are substantially the same in construction 20 as the lower rolls in that they also comprise tubular shafts 33 the ends of which are journaled in vertically adjustable slide bearings 34 mounted in ways 35 provided in the carriages 8 (Fig. 3). The intermediate portions of the shafts 33 are formed with spaced collars 36 upon which outer cylindrical shells 37 are fixed, preferably by shrinking. The collars 36 are provided with 25 staggered openings 38, similar to those described in connection with the lower rolls 11. The tubular shafts 33 are also provided with partitions 39 intermediate their ends (Fig. 3) and also with 30 openings 40 for establishing communication between the shafts 33 and the interior of the rolls 10 at the ends thereof.

40 A temperature controlling medium is also directed through the upper rolls 10 in opposite directions with respect to one another and in opposite directions with respect to that of the flow of the medium through the associated lower 45 rolls 11, from flexible inlet pipes 41 the upper ends of which are secured by means of clamping straps 42 to tubular flanged nipples 43 bolted to the outside surfaces of the slide bearings 34. The lower ends of the inlet pipes 41 are secured by 50 clamping straps 44 to flanged nipples 45 mounted on inlet valves 46 which control communication between the inlet pipes 41 and supply mains or conduits 47 located at the front and rear of the apparatus.

55 After passing through the upper rolls 10 the temperature controlling medium escapes from these rolls through flexible outlet pipes 48 the upper ends of which are secured by means of clamping straps 49 to flanged nipples 50 which 60 are bolted to the outer faces of the adjustable slide bearings 34 at the other side of the apparatus. The lower ends of the outlet pipes 48 are secured by clamping straps 51 to flanged nipples 52 which communicate with discharge mains 53 65 also located at the front and rear of the apparatus.

70 From an inspection of Fig. 13, it will be apparent that the construction and arrangement of the several inlet and outlet pipes is such that the temperature controlling medium flows 75 through the upper and lower rolls 10 and 11 of each of the pairs of rolls in opposite directions, and also that the direction of flow of the medium is in opposite directions when the corresponding rolls of the pairs of rolls are considered. This

tends toward an equalization in heat exchange longitudinally of the rolls.

The upper rolls 10 may be raised and lowered with respect to the lower rolls 11 in order to provide a sheet forming pass of the desired size 5 between the rolls of either or both of the pairs of rolls, by means of adjusting screws 54 having heads 55 (Fig. 3) at their lower ends which are rotatably confined within keepers 56 bolted to the upper surfaces of the slide bearings 34. The 10 upper portions of the adjusting screws 54 are threaded into worm nuts 57 which are confined between the upper ends of the carriages 8 and bars 58 secured to the carriages by plates 59. The worm nuts 57 are rotated in order to raise or 15 lower the adjusting screws 54, slide bearings 34, and rolls 10 journaled therein, by means of worms 60 (Fig. 2) which are fixed to stud shafts 61 journaled in the plates 59. Sprocket wheels 62 are fixed to the outer ends of the shafts 61 and are 20 rotated by sprocket chains 63 which pass around sprocket wheels 64 fixed to shafts 65. These shafts are journaled in swivelled or self-aligning bearings 66 secured to the sides of the carriages 8 and may be rotated from the front of the apparatus by hand wheels 67 in order to adjust the 25 positions of the slide bearings 34 simultaneously. The function of the self-aligning bearings 66 is to prevent these bearings from binding on the shaft 65 in the event that there is a slight lagging 30 or difference in movement between the carriages of each pair of carriages 8 when the pairs are swung apart, as will presently be described.

When the apparatus is in a position for fabricating one or two sheets the carriages 8 occupy 35 vertical positions with the lower rolls 11 substantially contiguous so that the circumferential surfaces of the rolls 10 and 11 of the pairs of rolls cooperate to define a substantially closed chamber 68 (Figs. 7 and 9 to 13). When in this 40 position the upper rolls 10, being of slightly less diameter than the lower rolls 11, are spaced from one another so as to form a restricted opening or neck 69 through which molten metal or other plastic material is adapted to be introduced 45 into the chamber 68 from a feeding device, such as a forehearth or ladle located above the rolls and indicated diagrammatically at 70. Such a feeding device may be provided with a single long narrow slot or orifice 71 (Fig. 8) or a series of 50 openings through which the material flows downwardly into the neck 69 in the form of a curtain 72 (Figs. 7 and 13), the flow being controlled by one or more gates or plungers 73.

The material is prevented from escaping from the chamber 68 lengthwise of the rolls by rotatable confining members 74 which abut the ends of the several rolls. These members are carried by a tubular shaft 75 which extends entirely through the chamber 68 and is journaled at its ends in downwardly extending hangers 76 the 60 upper ends of which are mounted for swinging movement on one or the other of the upper shafts 33. The members 74 are rotated by means of intermeshing gears 77 and 78, the former being fixed to the end members 74 and the latter being 65 fixed to the shaft 33 which carries the hangers 76.

A temperature controlled medium is also directed through the shaft 75 which supports the confining members 74, from an inlet pipe 79, one end of which is rigidly connected by means of a 70 flanged elbow 80 to one of the hangers 75 in communication with the tubular shaft 75. This pipe extends upwardly and over the tops of the carriages 8 and communicates at its outer end with the upper end of a flexible inlet pipe 81 75

which is secured thereto by means of a clamping strap 82. The lower end of the inlet pipe 81 is secured by a clamping strap 83 (Fig. 4) to a flanged nipple 84 fixed to a valve 85 which controls communication with one of the supply mains 26.

After passing through the tubular shaft 75 and the end members 74 carried thereby, the cooling medium escapes therefrom through a vertically extending outlet pipe 86 the lower end of which is fixed to the hanger 76 at the opposite ends of the rolls from the inlet pipe 79, by means of a flanged elbow 87. This outlet pipe extends upwardly and over the carriages 8 at the other 15 side of the apparatus and communicates at its outer end with the upper end of a flexible outlet pipe 88 which is secured thereto by means of a clamping strap 89. The lower end of the outlet pipe 88 is also secured by a clamping strap 90 to 20 a flanged nipple 91 which communicates with one of the discharge mains 32.

The curtains or series of streams 72 of molten metal or other material gravitating downwardly into the neck 69 from the orifice 71 in the fore- 25 hearth or ladle 70, may be subjected to a preliminary cooling operation by means of jets of a gaseous cooling medium such as air or steam projected from pipes 92 (Fig. 13) in opposite directions along opposite sides of the descending 30 metal. This cooling medium, if desired may be an inert gas so as to minimize oxidation. Also, it may be refrigerated if desired so as to accelerate the rate of cooling at this point. This cooling medium is preferably projected in directions opposite to the directions of flow of the 35 cooling medium through the adjacent upper roll so as to assist in obtaining a uniform dissipation of heat lengthwise of the neck 69 (Fig. 13).

The rolls 10 and 11 of both pairs of rolls are 40 rotated in the directions indicated by the arrows in Figures 7 and 9 in order to obtain a single sheet (a) from one side of the apparatus, (Figs. 7 and 9) by means of worm gears 93 and 94 which are fixed to the upper and lower tubular shafts 33 and 12 respectively, and which are 45 driven by upper and lower worms 95 and 96 fixed to shafts 97 journaled in bearings 98 carried by the carriages 8 at one side of the apparatus. The shafts 97 are each provided with a beveled pinion 99 at its lower end for intermeshing engagement 50 with beveled gears 100 rotatably mounted upon each of the supporting shafts 7. A worm wheel 101 is bolted to the side of each of the beveled gears 100 and each is driven by a worm 102 fixed to a horizontally extending jack shaft 103 which 55 is journaled in bearing blocks 104 mounted on the base 1. Also fixed to the jack shaft 103 is a worm wheel 105 which is driven by a worm 106 fixed to a transversely extending drive shaft 107 journaled in a bearing 108 (Fig. 5) provided on 60 one of the side frame members 3 and in a bearing block 109 carried by the base 1. The drive shaft 107 is driven by a variable speed electric motor M (Fig. 14) through the medium of any suitable connections.

65 It will be noted that the upper worms 95 are of sufficient length to maintain driving engagement with the worm gears 92 in all positions of adjustment of the upper rolls 10.

If it is desired to deliver a single sheet b from 70 the opposite side of the apparatus from that shown in Figs. 7 and 9, the rolls are rotated in the directions indicated by the arrows in Fig. 10, by means of supplemental worm gears 110 of 75 opposite lead which are slidably keyed to the

shaft 12 of the lower rolls 11 and which are driven by supplemental worms 111 of corresponding lead which are keyed to the shafts 97 for adjustment longitudinally thereof. Also by the proper selection of these gears and worms the rolls may be rotated in the directions indicated by the arrows in Fig. 11 in order to deliver two sheets a and b from opposite sides of the apparatus, and also to deliver a single sheet c downwardly between the lower rolls as indicated in 10 Fig. 12. In effecting the above described adjustments the worm which is in engagement with a particular worm gear is first loosened on the shaft 97 and slid longitudinally out of engagement with its intermeshing worm wheel. This 15 worm wheel is then loosened and slid longitudinally along the shaft 12 and the worm gear of opposite lead is then slid into operative position and fixed to the shaft 12. The worm of corresponding lead is then slid along the shaft 97 20 and in intermeshing relation with this gear wheel and fixed in position.

It will be noted from inspection of Figs. 9 to 25 12, that the adjacent surfaces of the contiguous rolls either move in opposite directions or move inwardly. This prevents material from escaping from the chamber 68 between any of the rolls except those defining the sheet forming pass or passes.

The carriages 8 are swung apart, as shown in 30 Fig. 8, so as to interrupt the supply of material to the rolls and also to discharge material delivered to the chamber 68, by means of horizontally extending non-rotatable threaded rods 112 the inner ends of which are slidably mounted in 35 bearing blocks 113 carried by the side frames 3, and the outer ends of which in spaced bearing blocks 114 carried by the plates 4. Links 115 are pivotally connected at their upper ends, as indicated at 116 (Fig. 5) to the carriages 8 and 40 at their lower ends, as at 117 to blocks 118 which are threaded onto the rods 112 for adjustment longitudinally thereof. The rods 112 are shifted horizontally by means of worm nuts 119 which are threaded onto the rods 112 between the 45 spaced bearing blocks 114. These nuts are rotated by means of worms 120 which are fixed to shafts 121 between spaced bearing blocks 122 which are carried by the bearing blocks 114 and in which the shafts 121 are journaled. The 50 shafts 121 extend along each side of the apparatus and may be rotated from one side of the apparatus by means of hand wheels 123 so as to swing the carriages 8 simultaneously.

It will be noted that the shafts 97 extend 55 radially with respect to the axis of the supporting shaft 7 so that the beveled pinions 99 maintain driving engagement with the beveled gears 100 in all positions of the carriage 8. This insures that the rolls 10 and 11 may be rotated when the same 60 are separated, as indicated in Fig. 8, so as to free or assist in freeing metal adhering thereto.

The base 1 is provided with an opening 124 directly beneath the rolls so that when the rolls are swung apart the material in the chamber 68 65 may be discharged into a cullet pit or the like 125 located beneath the apparatus.

The above described lateral swinging movement of the rolls may also be employed to adjust the lower rolls 11 relative to one another so as 70 to provide a sheet forming pass between these rolls, when it is desired to obtain the single sheet c delivered downwardly between the rolls 11, as indicated in Fig. 12.

From the foregoing it will be apparent that an 75

apparatus is provided in which the rolls of two pairs of rolls cooperate to define a substantially closed chamber for receiving molten metal delivered from above. This arrangement of the 5 rolls has several advantages in that it minimizes oxidation of the metal in the chamber during the period that it is being cooled preparatory to passing between the rolls to be fabricated thereby into sheet form. Also, heat is extracted from 10 the metal substantially uniformly in a zone surrounding the entire body of metal in the chamber 68 so as to provide layers of plastic metal of substantially equal areas and of approximately 15 the same temperature adjacent to the upper and lower rolls in the vicinity of the sheet forming pass. The movement of the rolls carries these layers of metal through the pass where they are united to form a sheet having uniformly cooled upper and lower surfaces or skins.

20 Obviously, if the cooling and shaping rolls 10 and 11 are rotated too rapidly with respect to the rate at which the metal in the chamber 68 dissipates its heat, the metal will not become sufficiently solidified to retain its sheet form after 25 passing through the pass between the rolls. On the other hand, if the rolls are rotated too slowly the metal may reach such a degree of solidity as to subject the rolls to excessive strain if not actually "freezing" while in contact therewith.

30 Also, the temperature of the metal as well as that of the cooling medium flowing through the rolls may fluctuate to such an extent and so frequently as to render any constant roll speed impractical.

35 According to the present invention these difficulties and uncertainties are avoided by the provision of thermo-responsive means for automatically varying the speed of the motor M and that of the rolls 10 and 11 in accordance with the 40 temperature of the metal and any fluctuations therein.

With reference to Fig. 14 of the drawings, the armature winding of the motor M is shown as being energized by direct current which traverses 45 a circuit from a suitable source, such as positive bus wire 126, through wire 127, armature winding of motor M, and wire 128, to negative bus wire 136. The field winding of motor M is also energized by current which traverses a circuit from positive 50 bus wire 126, wires 127 and 127', field winding f of motor M, wire 128', manually operable switch 129, wire 130, manually adjustable rheostat 131, wire 132, back contacts 133, and connecting wires 134 of a series of relays, indicated by the letter 55 w with exponents according to their location, and wire 135 to negative bus wire 136. Under these conditions the motor M will drive the cooling and shaping rolls 10 and 11 at a speed determined by the manual adjustment of the rheostat 131 60 and the rolls will fabricate a sheet, as previously described, if the metal dissipates its heat at the proper rate at such roll speed.

The speed of the motor M is automatically controlled by a thermocouple T which is positioned 65 adjacent to the molten metal within the forehearth or ladle 70 or within the chamber 8 between the rolls 10 and 11 or both, so that the temperature thereof will generate an electric current in the well known manner in a circuit including wires 137 and 138 connecting the terminals of the thermocouple T with those of a galvanometer G. The hot end of the thermocouple 70 T is suitably connected to the outer end of a metal bar 139 the inner end of which is exposed 75 to the hot metal and which is provided with a

suitable heat insulating covering 140 so as to insure a uniform drop in temperature from end to end. The temperature of the inner end of the bar 139 is that of the metal but the drop in temperature longitudinally of the bar is such as to prevent the thermocouple T from being damaged by being subjected to excessive heat. However, sufficient heat is transmitted to the thermocouple T by conduction to insure that the same will operate properly in accordance with fluctuations in the temperature of the metal within the forehearth 70.

The galvanometer G operates a disk or shutter 141 provided with an aperture 142 through which light rays emanating from a source of light, 15 such as an electric lamp 143, may be progressively admitted into a series of chambers c. Located within each of the chambers c is a selenium cell or resistor s and also a lens l for focusing the light admitted through the aperture 142 20 upon the light sensitive element of the cells s.

When the temperature of the metal within the forehearth 70 reaches a predetermined degree, the galvanometer G will swing the shutter 141 to a position in which its aperture 142 registers with 25 the first chamber c¹ of the series so that light from the lamp 143 will be focused upon the selenium cells s¹, thus rendering the light sensitive element thereof sufficiently conductive to effect the energizing of relay w¹ by current traversing 30 a circuit from positive bus wire 126, through a manually adjustable resistance 144, wire 145, light sensitive element of the selenium cells s¹, wire 146, winding of relay w¹, and wire 147 to the negative bus wire 126. The energizing of the 35 relay w¹ causes it to open its back contact 133 and to close a front contact 148 thereof. This opens the circuit previously traced for the motor M but establishes an auxiliary circuit therefor through the first section r¹ of a resistance element 40 R, front contact 148 of relay w¹ and wire 149 to the negative bus wire 136. The introduction of 45 this additional resistance r¹ into the motor circuit causes the speed of the motor and that of the rolls to decrease a predetermined amount so as to allow a greater time for the metal to dissipate its heat and reach the desired degree of plasticity before passing between the rolls.

If the speed of the rolls is still too high to permit the metal to become sufficiently plastic to 50 retain its sheet form after passing between the rolls, the galvanometer G will swing the shutter 141 until the aperture 142 therein registers with the next adjacent chamber c² of the series so that light from the lamp 143 will render the next 55 succeeding selenium cell s² electrically conductive and cause the energizing of the relay w². The energizing of the relay w² introduces the next section r² of the resistance R in the motor circuit so as to cause the motor M to rotate at 60 a still further reduced speed. It will be understood that when the back contact 133 of one of the preceding relays w is opened, as above described, the back contact 133 of the preceding 65 relay w is closed so that the current will be compelled to traverse all of the sections r of the resistance R which are introduced into the circuit by the closing of the front contact of the relay last energized. The above described operations are repeated successively until the desired amount 70 of resistance is included in the circuit of the motor M.

It will be understood that the chambers c are impervious to light except when the aperture 142 in the shutter is moved into registry therewith. 75

Also, it will be understood that suitable amplifying means may be provided in the circuits of the several selenium cells if so desired.

For the purpose of illustration, the current is schematically shown as passing directly through the contacts 190 and 201 of the relays *w*, but it will be appreciated by those skilled in the art that the contacts of these relays may be employed to energize auxiliary circuits including circuit makers and breakers of a type particularly adapted to carry the current employed, especially where normally high current values are to be dealt with.

The hereinabove described control system is given by way of example only, it not being intended to limit the instant improvements to any particular circuit or circuits.

If desired, the carriages 8 may be mounted on rollers traversing tracks of channel shape so as to permit them to be moved bodily toward and away from one another in a rectilinear direction. In such event elongated worms, such as the worms 95, are substituted for the worms 102 so as to maintain driving connection with the rolls during 25 and after their separation.

In addition, vertically reciprocatory confining members may be substituted for the rotatable members 14. Confining members of this type project upwardly further than the rotary type 30 illustrated and consequently permit the metal to completely fill the neck 69, as shown in Figs. 9 to 13.

Also, if desired the carriages may be moved towards and away from one another by means 35 of hydraulic jacks operating simultaneously.

Such modifications require little or no additional change in the structure hereinbefore described.

When metals having a relatively high melting point, such as iron or steel, are rolled it may be found desirable to provide additional pairs of rolls on one or both sides of the apparatus so as to provide a series of chambers communicating with one another through relatively narrow 45 openings between the rolls of the several pairs. These openings may be made adjustable and may function as sheet forming passes.

In this particular arrangement the metal has considerable time within which to dissipate its 50 heat and become plastic. If the metal becomes plastic before passing through the entire series of chambers it will be shaped into sheet form by one of the intermediate pairs of rolls, the rolls subsequently encountered functioning as additional reducing, smoothing, supporting and cooling means. On the other hand, if the metal does not become plastic until it reaches the last or outermost pair of rolls, these rolls perform the shaping function, the preceding rolls merely functioning as feeding and cooling means.

The several pairs of rolls may be mounted in contiguous relation so as to exclude as much as possible the entrance of air from the outer atmosphere into the chambers, thus preventing or 65 minimizing the oxidation of the metal as it passes from chamber to chamber. The rate of dissipation of heat from the metal passing through the chambers may be controlled in accordance with a temperature gradient determined by the temperature of the metal or the characteristics of the particular metal being rolled, by circulating a cooling medium in controllable amounts through the several pairs of rolls. Also, the entire series of rolls may be inclosed within a suitable housing 70 through which an inert cooling gas may be circu- 75

lated. An apparatus such as that just described is the subject of applicant's copending application, Serial No. 734,350 filed July 9, 1934, which constitutes a continuation in part of this application.

Other modifications and changes in proportion and arrangement of the several necessary elements constituting the invention may be made by those skilled in the art without departing from the nature and scope of the invention as defined 10 in the appended claims.

I claim:

1. The method of rolling a sheet or bar from iron or steel delivered in a molten condition which comprises the steps of introducing the 15 molten metal into a substantially closed chamber defined by two pairs of rolls arranged in side-by-side relation; rendering the metal in contact with the surfaces of the rolls relatively plastic throughout zones of substantially coextensive areas above and below the line of nearest approach between the rolls of said pairs of rolls; by circulating a heat dissipating medium through said rolls; and uniting the plastic metal of the zones adjacent to at least one of said pairs of 20 rolls by passing the same laterally between such rolls, thus compressing the same to form a sheet or bar cooled on opposite sides substantially equal 25 depths.

2. The method of rolling a plurality of sheets 30 or bars simultaneously from iron or steel delivered in a molten condition, which comprises the steps of introducing the molten metal into a substantially closed chamber defined by two pairs of rolls arranged in side-by-side relation; rendering the metal in contact with the surfaces of the rolls relatively plastic throughout zones of substantially coextensive areas above and below the line of nearest approach between the rolls of 35 said pairs of rolls, by circulating a heat dissipating medium through said rolls; and uniting the plastic metal of the zones on opposite sides of said chamber by passing the same laterally in opposite directions between the rolls of the adjacent pairs of rolls, thus compressing the same 45 and simultaneously forming two sheets or bars each cooled on opposite sides substantially equal depths.

3. Apparatus of the character described comprising an assembly of more than two rolls arranged to define a substantially closed chamber 50 for receiving a supply of molten metal, a restricted throat through which molten metal is adapted to be introduced into said chamber, and a sheet forming pass communicating with said chamber; means for cooling said rolls to extract heat from the metal in said chamber, said rolls presenting cooling surfaces of substantially equal areas to the heated metal in said chamber, thus rendering the metal in contact therewith relatively plastic in zones of equal areas on opposite 55 sides of said pass; and means for rotating said rolls to move the plastic metal of said zones outwardly through said pass to be united by the pressure of said rolls, thus forming a sheet cooled 60 on opposite sides substantially equal depths.

4. Apparatus of the character described comprising an assembly of four rolls arranged to define a substantially closed chamber for receiving a supply of molten metal, a restricted throat 70 through which molten metal is adapted to be introduced into said chamber, and a sheet forming pass communicating with said chamber; means for cooling said rolls to extract heat from the metal in said chamber, said rolls presenting cool- 75

ing surfaces of substantially equal areas to the heated metal in said chamber, thus rendering the metal in contact therewith relatively plastic in zones of equal areas on opposite sides of said 5 pass; and means for rotating said rolls to move the plastic metal of said zones outwardly through said pass to be united by the pressure of said rolls, thus forming a sheet cooled on opposite sides substantially equal depths.

10. 5. Apparatus of the character described comprising an assembly of four rolls arranged to define a substantially closed chamber for receiving a supply of molten metal; a restricted throat through which molten metal is adapted 15 to be introduced into said chamber, and two opposed sheet forming passes communicating with said chamber; means for cooling said rolls to extract heat from the metal in said chamber, said rolls presenting cooling surfaces of substantially equal areas to the heated metal in said chamber, thus rendering the metal in contact therewith relatively plastic in zones of equal areas on opposite sides of said passes; and means 20 for rotating said rolls to move the plastic metal 25 of said zones outwardly through said passes to be united by the pressure of said rolls, thus simultaneously forming two sheets cooled on opposite sides substantially equal depths.

6. Apparatus of the character described comprising two pairs of superposed rolls arranged in side-by-side relation and cooperating with one another to define a substantially closed chamber therebetween for receiving a supply of molten metal, the lower rolls of said pairs of rolls being 30 disposed in contiguous relation to support the metal in said chamber and to prevent the escape of metal therebetween, the upper rolls of said pairs of rolls being disposed in slightly spaced relation to provide a restricted opening or throat 35 through which molten metal is adapted to be introduced into said chamber, and the rolls of certain of said pairs of rolls being spaced to provide a sheet forming pass; means for cooling said rolls, the rolls of said pairs of rolls presenting 40 cooling surfaces of substantially equal areas to the heated metal in said chamber, thus rendering the metal in contact therewith relatively plastic in zones of equal areas above and below said pass; and means for rotating said 45 rolls to move the metal in said throat downwardly into said chamber and the metal in said chamber laterally outwardly through said pass to unite the plastic metal of said zones under pressure, thus forming a sheet or bar cooled on 50 opposite sides substantially equal depths.

7. Apparatus of the character described comprising two pairs of superposed rolls arranged in side-by-side relation and cooperating with one another to define a substantially closed chamber 60 therebetween for receiving a supply of molten metal, the lower rolls of said pairs of rolls being disposed in contiguous relation to support the metal in said chamber and to prevent the escape of metal therebetween, the upper rolls 65 of said pairs of rolls being disposed in slightly spaced relation to provide a restricted opening or throat through which molten metal is adapted to be introduced into said chamber, and the rolls of both of said pairs of rolls being spaced to provide two opposed sheet forming passes; means for cooling said rolls, the rolls of said pairs of rolls presenting 70 cooling surfaces of substantially equal areas to the heated metal in said chamber, thus rendering the metal in contact therewith relatively plastic in zones of equal areas above and

below said passes; and means for rotating said rolls to move the metal in said throat downwardly into said chamber and the metal in said chamber laterally outwardly in opposite directions through said passes to unite the plastic metal of said zones under pressure, thus simultaneously forming two sheets or bars cooled on opposite sides substantially equal depths. 5

8. Apparatus of the character described comprising two pairs of superposed rolls arranged in side-by-side relation and cooperating with one another to define a substantially closed chamber therebetween for receiving a supply of molten metal, the rolls of said pairs of rolls being disposed in contiguous relation to prevent the escape of metal therebetween the upper rolls of said pairs of rolls being disposed in slightly spaced relation to provide a restricted opening or throat through which molten metal is adapted to be introduced into said chamber, and the lower rolls of said pairs of rolls being spaced to provide a sheet forming pass; means for cooling said rolls, the rolls of said pairs of rolls presenting cooling surfaces of substantially equal areas to the heated metal in said chamber, thus rendering the metal in contact therewith relatively plastic in zones of equal areas on opposite sides of said pass; and means for rotating said rolls to move the metal in said throat downwardly into said chamber and the metal in said chamber downwardly through said pass to unite the plastic metal of said zones under pressure, thus forming a sheet or bar cooled on opposite sides substantially equal depths. 10 15 20 25 30 35

9. Apparatus such as described in claim 3, including also means responsive to the temperature of the metal before it passes the shaping rolls for controlling the speed of rotation of the rolls. 35

10. Apparatus such as described in claim 4, including also means responsive to the temperature of the metal before it passes the shaping rolls for controlling the speed of rotation of the rolls. 40

11. Apparatus such as described in claim 5, including also means responsive to the temperature of the metal before it passes the shaping rolls for controlling the speed of rotation of the rolls. 45

12. Apparatus such as described in claim 6, including also means responsive to the temperature of the metal before it passes the shaping rolls for controlling the speed of rotation of the rolls. 50

13. Apparatus such as described in claim 7, including also means responsive to the temperature of the metal before it passes the shaping rolls for controlling the speed of rotation of the rolls. 55

14. Apparatus such as described in claim 8, including also means responsive to the temperature of the metal before it passes the shaping rolls for controlling the speed of rotation of the rolls. 60

15. Apparatus of the character described comprising an assembly of more than two rolls arranged to define a substantially closed chamber for receiving a supply of molten metal, a restricted throat through which molten metal is adapted to be introduced into said chamber, and a sheet-forming pass communicating with said chamber; means for cooling said rolls to extract heat from the metal in said chamber, said rolls presenting cooling surfaces of substantially equal areas to the heated metal in said chamber, thus rendering the metal in contact therewith rela- 65 70 75 80 85 90

tively plastic in zones of equal areas on opposite sides of said pass; and means responsive to the temperature of the metal before it passes out of said closed chamber for automatically controlling the speed of rotation of the sheet-forming rolls.

5 16. Apparatus of the character described, comprising an assembly of more than two superposed horizontally disposed cooling rolls in side by side relation, arranged and cooperating to define a substantially closed receptacle for receiving a supply of molten metal; variable speed driving mechanism for rotating the rolls to move the metal from the said chamber outwardly between certain of them to be shaped thereby into a continuous sheet, and means responsive to the temperature of the metal before it passes the shaping rolls for automatically controlling the speed of operation of the means which rotate the rolls.

10 17. Apparatus of the character described comprising two pairs of superposed horizontally disposed cooling rolls arranged in side by side relation and cooperating to define a substantially closed chamber therebetween, the uppermost rolls of said pairs being disposed in spaced relationship to each other to provide a restricted opening through which molten metal is adapted to be introduced into the chamber, variable speed driving means for the said rolls arranged to rotate them so as to move the metal from the chamber outwardly between certain of the rolls in the said pairs to be shaped thereby into a continuous sheet, means for adjusting certain of the rolls whereby the pass through which the metal moves when being shaped into a sheet may be changed 15 to form sheets of different thicknesses as desired, and means responsive to the temperature of the metal before it is shaped and passed out of the said chamber for controlling the variable speed mechanism.

20 18. Apparatus of the character described comprising two pairs of superposed horizontally disposed rolls arranged in side by side relation and cooperating to define a substantially closed chamber therebetween, the upper rolls of said pairs of rolls being spaced from one another to provide a restricted throat through which plastic material is adapted to be introduced into said chamber from above; confining members mounted for longitudinal engagement with the ends of said rolls for preventing the escape of material from said chamber longitudinally of said rolls; and means for moving said confining members relatively to said rolls to minimize any tendency for material to adhere thereto.

25 19. Apparatus of the character described comprising two pairs of superposed horizontally disposed rolls arranged in side by side relation and cooperating to define a substantially closed chamber therebetween, the upper rolls of said pairs of rolls being spaced from one another to provide a restricted throat through which plastic material is adapted to be introduced into said chamber from above; confining members mounted for longitudinal engagement with the ends of said rolls for preventing the escape of material from said chamber longitudinally of said rolls; and means for rotating said confining members relatively to said rolls to minimize any tendency for material to adhere thereto.

30 20. Apparatus of the character described comprising two pairs of superposed horizontally disposed rolls arranged in side by side relation and cooperating to define a substantially closed chamber therebetween, certain corresponding rolls of said pairs of rolls being spaced from one another

5 to provide a restricted throat through which plastic material is adapted to be introduced into said chamber; rotatable members disposed adjacent to the ends of said rolls for preventing the escape of material from said chamber longitudinally of said rolls; means for rotating said members relatively to said rolls to minimize any tendency for material to adhere thereto; means for rotating said rolls to move material from said chamber between the rolls of at least one of said pairs of rolls to be shaped thereby; and means for effecting bodily movement between said pairs of rolls and between at least one of said pairs of rolls and said confining members to discharge material from said chamber, said rolls and confining members being rotatable during and after the bodily movement thereof to free material adhering thereto.

10 21. Apparatus of the character described comprising two pairs of superposed horizontally disposed rolls arranged in side by side relation and cooperating to define a substantially closed chamber therebetween, certain corresponding rolls of said pairs of rolls being spaced from one another to provide a restricted throat through which molten metal is adapted to be introduced into said chamber, said rolls presenting cooling surfaces of substantially equal areas to the metal in said chamber; means for rotating said rolls to move metal from said chamber between the rolls of at least one of said pairs of rolls to be shaped thereby; and manually controlled means operable from one side of said apparatus for bodily moving at least one of said pairs of rolls out of operative relation to the other to discharge metal from said chamber.

15 22. Apparatus of the character described comprising two pairs of superposed horizontally disposed rolls arranged in side by side relation and cooperating to define a substantially closed chamber therebetween, certain corresponding rolls of said pairs of rolls being spaced from one another to provide a restricted throat through which molten metal is adapted to be introduced into said chamber, said rolls presenting cooling surfaces of substantially equal areas to the metal in said chamber; bearings for said rolls at the ends thereof; means for rotating said rolls to move metal from said chamber between the rolls of at least one of said pairs of rolls to be shaped thereby into a sheet; and manually controlled means operable from one side of said apparatus for simultaneously moving the bearings of one of the rolls of one of said pairs of rolls to adjust such roll relative to the other roll of the same pair, to vary the thickness of the sheet fabricated thereby.

20 23. Apparatus of the character described comprising two pairs of superposed horizontally disposed rolls arranged in side by side relation and cooperating to define a substantially closed chamber therebetween, certain corresponding rolls of said pairs of rolls being spaced from one another to provide a restricted throat through which molten metal is adapted to be introduced into said chamber, said rolls presenting cooling surfaces of substantially equal areas to the metal in said chamber; means for rotating said rolls to move metal from said chamber between the rolls of at least one of said pairs of rolls to be shaped thereby; and means for bodily moving at least one of said pairs of rolls out of operative relation to the other to discharge metal from said chamber.

25 24. Apparatus of the character described comprising two pairs of superposed horizontally dis-

posed rolls arranged in side-by-side relation and cooperating to define a substantially closed chamber therebetween; the upper rolls of said pairs of rolls being spaced from one another to provide 5 a restricted throat through which molten metal is adapted to be introduced into said chamber from above, said rolls presenting cooling surfaces of substantially equal areas to the metal in said chamber; means for rotating said rolls to move 10 metal outwardly from said chamber between the rolls of at least one of said pairs of rolls to be shaped thereby; and means for selectively moving said pairs of rolls bodily away from one another while still rotating to discharge metal from said 15 chamber and to free said rolls from metal in contact therewith.

25. Apparatus of the character described comprising two pairs of superposed horizontally disposed rolls arranged in side by side relation and 20 cooperating to define a substantially closed chamber therebetween, the upper rolls of said pairs of rolls being spaced from one another to provide a restricted throat through which molten metal is adapted to be introduced into said chamber from 25 above, said rolls presenting cooling surfaces of substantially equal areas to the metal in said chamber; means for separating said pairs of rolls to discharge metal from said chamber; means for rotating said rolls when together to 30 move metal from said chamber outwardly between the rolls of one of said pairs of rolls to be shaped thereby, and also when separated to free said rolls from metal in contact therewith; and means for separating the rolls of at least one of 35 said pairs of rolls while the same are rotating.

26. Apparatus for use in fabrication of sheets or bars directly from molten metal comprising two pairs of rotatable rolls of approximately equal diameters set opposite each other whereby is 40 formed between them an enclosed space for the collection of a body of molten metal bounded by the four moving surfaces of the rolls, the upper opposite rolls of the pairs being spaced apart to form between them a pass for the entrance of 45 molten metal to the enclosed space between the rolls, and other of the rolls being spaced apart to form an exit pass for the formed sheet or bar, means for cooling the rolls, and means for driving the rolls so as to move the metal after entering 50 the said enclosed space, about within such space, and finally out through the exit pass, the rolls operating to extract heat directly from the body of metal in the enclosed space on practically all surfaces of said body and without considerable 55 exposure to atmospheric air.

27. Apparatus of the character described comprising two pairs of superposed horizontally disposed rolls arranged in side by side relation and cooperating to define a substantially closed chamber therebetween, the upper rolls of said pairs of rolls being spaced from one another to provide a restricted throat through which molten metal is adapted to be introduced into said chamber from 60 above, said rolls presenting cooling surfaces of substantially equal areas to the metal in said chamber; means for rotating the upper rolls of 65 said pairs of rolls with the inner portions of the circumferential surfaces thereof moving downwardly to carry metal into said chamber; and means for rotating the lower rolls of said pairs of rolls in selected directions to move metal optionally from said chamber outwardly between the rolls of one of said pairs of rolls to be shaped 70 thereby into a single sheet, and between the rolls 75

of both of said pairs of rolls simultaneously to be shaped thereby into a pair of sheets.

28. Apparatus of the character described comprising two pairs of superposed horizontally disposed rolls arranged in side by side relation and cooperating to define a substantially closed chamber therebetween, the upper rolls of said pairs of rolls being spaced from one another to provide a restricted throat through which molten metal is adapted to be introduced into said chamber 10 from above, said rolls presenting cooling surfaces of substantially equal areas to the metal in said chamber; means for rotating the upper rolls of said pairs of rolls with the inner portions of the circumferential surfaces thereof moving downwardly to carry metal into said chamber; and means for rotating the lower rolls of said pairs of rolls in selected directions to move metal optionally from said chamber outwardly between the rolls of one of said pairs of rolls to be shaped 15 thereby into a single sheet, between the rolls of both of said pairs of rolls simultaneously to be shaped thereby into a pair of sheets, and downwardly between the lower rolls of said pairs of rolls to be shaped thereby into a single sheet. 20

29. Apparatus of the character described comprising two pairs of superposed horizontally disposed rolls arranged in side by side relation and cooperating to define a substantially closed chamber therebetween, the upper rolls of said 30 pairs of rolls being spaced from one another to provide a restricted throat through which material fluid when heated is adapted to be introduced into said chamber from above, said rolls presenting cooling surfaces of substantially equal 35 areas to the material in said chamber; means for rotating said rolls to move material from said chamber outwardly between the rolls of a selected pair of rolls to be shaped thereby into a sheet; and means for directing a cooling medium through one of the rolls of said selected pair of rolls in one direction and through the other roll of said selected pair of rolls in an opposite direction to extract heat from the material passing between the rolls of said selected 40 pair of rolls uniformly transversely of said sheet. 45

30. Apparatus of the character described comprising two pairs of superposed horizontally disposed rolls arranged in side by side relation and cooperating to define a substantially closed 50 chamber therebetween, the upper rolls of said pairs of rolls being spaced from one another to provide a restricted throat through which material fluid when heated is adapted to be introduced into said chamber from above, said rolls presenting cooling surfaces of substantially equal 55 areas to the material in said chamber; means for rotating said rolls to move material from said chamber outwardly between the rolls of at least one of said pairs of rolls to be shaped thereby 60 into a sheet; and means for directing a cooling medium through the upper roll of one of said pairs of rolls in one direction and through the upper roll of the other of said pairs of rolls in an opposite direction, to extract heat from the 65 material in said throat uniformly longitudinally of said rolls.

31. Apparatus of the character described comprising two pairs of superposed horizontally disposed rolls arranged in side by side relation and 70 cooperating to define a substantially closed chamber therebetween, the upper rolls of said pairs of rolls being spaced from one another to provide a restricted throat communicating with 75 said chamber; means located above said rolls for

- delivering molten metal to said throat in a relatively thin curtain extending longitudinally of said rolls; means for directing a cooling medium through said rolls to extract heat from the metal in said chamber and render the same relatively plastic, said rolls presenting cooling surfaces of substantially equal areas to the metal in said chamber; means for rotating said rolls to move metal from said chamber outwardly between the rolls of at least one of said pairs of rolls to be shaped thereby; and means for directing a gaseous cooling medium adjacent to said curtain of metal to extract heat therefrom prior to the contact of said metal with said rolls. 5
32. Apparatus of the character described comprising two pairs of superposed horizontally disposed rolls arranged in side by side relation and cooperating to define a substantially closed chamber therebetween, the upper rolls of said pairs of rolls being spaced from one another to provide a restricted throat communicating with said chamber; means located above the rolls for delivering molten metal to the said throat in a relatively thin liquid curtain extended longitudinally of the rolls; means for directing a cooling medium through the rolls to extract heat from the metal in the chamber and render the same relatively plastic, the said rolls presenting cooling surfaces of approximately equal areas to the metal in the said chamber; means for rotating the rolls to move the metal from the said chamber outwardly between the rolls of at least one of said pairs of rolls to be shaped thereby and means for directing a gaseous medium adjacent to the said liquid curtain of metal prior to contact of the metal with said rolls. 10
33. Apparatus of the character described comprising two pairs of superposed horizontally disposed rolls arranged in side by side relation and cooperating to define a substantially closed chamber therebetween, the upper rolls of said pairs of rolls being spaced from one another to provide a restricted throat communicating with said chamber; means located above said rolls for delivering molten metal to said throat in a relatively thin curtain extending longitudinally of said rolls; means for directing a cooling medium through said rolls to extract heat from the material in said chamber and render the same relatively plastic, said rolls presenting cooling surfaces of substantially equal areas to the metal in said chamber; means for rotating said rolls to move metal from said chamber outwardly between the rolls of at least one of said pairs of rolls to be shaped thereby; and means for directing parallel streams of a gaseous cooling medium in opposite directions along opposite sides of said curtain of metal to extract heat therefrom uniformly longitudinally of said rolls prior to the contact of said metal with said rolls. 15
34. Apparatus of the character described comprising two pairs of superposed horizontally disposed rolls arranged in side by side relation and cooperating to define a substantially closed chamber therebetween, certain corresponding rolls of said pairs of rolls being spaced from one another to provide a restricted throat through which molten metal is adapted to be introduced into said chamber, said rolls presenting cooling surfaces of substantially equal areas to the metal in said chamber; floating bearings for said lower rolls; back-up rolls journaled in fixed bearings for supporting said lower rolls; and means for rotating the rolls of at least one of said pairs of rolls to move metal from said chamber between the rolls of such pair to be shaped thereby into a sheet. 20
35. Apparatus of the character described comprising two pairs of superposed horizontally disposed hollow rolls arranged in side by side relation and cooperating to define a substantially closed chamber therebetween, certain corresponding rolls of said pairs of rolls being spaced from one another to provide a restricted throat through which material fluid when heated is adapted to be introduced into said chamber, said rolls presenting cooling surfaces of substantially equal areas to the material in said chamber; tubular shafts for supporting said hollow rolls; movable bearings for said shafts; conduits fixed to said bearings and movable therewith for supplying a cooling medium to said hollow rolls; and means for rotating said rolls to move material from said chamber between the rolls of at least one of said pairs of rolls to be shaped thereby. 25
